INVENTOR

BY Victor J. Evans

WITNESS:

ATTORNEY

UNITED STATES PATENT OFFICE.

CHARLES H. THORNDELL, OF CONNELLSVILLE, PENNSYLVANIA.

FURNACE DOOR.

Application filed August 28, 1922. Serial No. 584,782.

To all whom it may concern:

Be it known that I, CHARLES H. THORNDELL, a citizen of the United States, residing at Connellsville, in the county of Fayette and State of Pennsylvania, have invented new and useful Improvements in Furnace Doors, of which the following is a specification.

This invention relates to furnace doors, and more particularly to the means for securing a liner to the inner face of the door.

One of the main objects of the invention is to provide simple and efficient means whereby a projecting member or liner may be quickly and easily secured in position adjacent to the inner face of a furnace door, this liner acting in a known manner to protect the door from being damaged by the intense heat generated within the furnace. A further object is to provide means of the character stated of simple construction which may be readily produced at small cost and will not necessitate any material changes in the patterns at present used for casting furnace doors. Further objects will appear from the detailed description.

In the drawings:—

Figure 1 is an elevation of the door.

Figure 2 is a section through the door.

Figure 3 is a view similar to Fig. 2 of a modified form.

In practicing the invention, door 1, which is mounted in a suitable frame A in a known manner, and is formed of cast iron in a known manner, is provided with a central outwardly projecting boxing or neck 2 of rectangular cross-section which is reinforced by ribs 3 extending from the corners of neck 2 to the corners of the door. In the form illustrated in Fig. 2 I provide a cast iron liner 4 which is reinforced by brace ribs 5 provided on its inner face. This liner is provided, on its outer face, with an outwardly projecting block 6 which fits snugly in neck 2, this block being provided with a central bore for reception of a tapered pin 7 which is inserted through aligned openings in the top and bottom walls of neck or boxing 2. This pin serves to effectually secure the liner to the door, as illustrated. Preferably, though not necessarily, the door is provided on its inner face with spacing elements 1^a which serve to hold liner 4 in spaced relation to the inner face of the door

providing an air space 8 between the door 55 and the liner. When it is desired to replace the liner, pin 7 is removed after which the liner is removed from the door by pulling block 6 out of boxing 2, a new liner being placed in position and the pin 7 driven 60 through the block of the new liner and the top and bottom walls of boxing 2.

In the form illustrated in Fig. 3 the spacing elements 1^a are omitted from the inner face of door 1^b and liner 4 is replaced by a liner 4^a of fireclay or other suitable refractory material, line 4^a having a block 6^a which fits into boxing 2 and is secured by pin 7.

It will be seen that I have produced very simple and efficient means for securing the liner to the inner face of a furnace door, this means permitting a liner to be quickly and easily removed and replaced thus effecting a material saving in time.

What I claim is:—

1. In combination with a furnace door provided with an outwardly projecting central boxing of non-circular cross-section, a liner at the inner face of the door and provided with an integral outwardly projecting element fitting into said boxing, and a member inserted through said element and the boxing and coacting therewith to secure the liner in operative relation to the door.

2. In combination with a furnace door 85 provided with an outwardly projecting central boxing of non-circular cross-section and with reinforcing ribs extending from the boxing and integrally connecting the same with the door, a liner at the inner 90 face of the door and provided with an integral outwardly projecting element fitting into said boxing, and a tapered pin inserted through the boxing and the projecting element of the liner.

3. In combination with a furnace door provided with an outwardly projecting boxing of non-circular cross-section, a liner positioned adjacent to the inner face of the door and provided with an integral outwardly projecting element fitting snugly into said boxing, and a member inserted through said element of the liner and the boxing and acting to force the liner toward the door and to secure the door and 105 the liner together.

In testimony whereof I affix my signature.
CHARLES H. THORNDELL.
